UNITED STATES PATENT OFFICE.

ARTHUR VAN RAALTE, OF NEW YORK, N. Y., ASSIGNOR TO VAN RAALTE COMPANY, INC., OF NEW YORK, N. Y., A CORPORATION OF NEW YORK.

DESIGN FOR A TEXTILE FABRIC.

• 60,277.

Specification for Design.

Patented Jan. 17, 1922.

Application filed May 3, 1921. Serial No. 466,617. Term of patent 3½ years.

To all whom it may concern:

Be it known that I, ARTHUR VAN RAALTE, a citizen of the United States, residing in the city, county, and State of New York, have invented a new, original, and ornamental Design for a Textile Fabric, of which the following is a specification, reference being had to the accompanying drawing, forming part hereof, in which the figure shown is a face view of a section of the fabric showing my new design.

I claim:

The ornamental design for a textile fabric, as shown.

ARTHUR VAN RAALTE.
